ELLIPSOGRAPH

Nathan Rabinowitz, Brooklyn, N. Y.

Application May 8, 1945, Serial No. 592,568

8 Claims. (Cl. 33—30)

1

This invention relates to drawing instruments, and more particularly to those of the character employed for drawing oval or elliptical figures.

While efforts have been made in the past to produce satisfactory instruments of this character by means of which elliptical figures could be drawn, wholly satisfactory results have not been obtained particularly for the production of relatively small and accurate ellipses.

The present invention therefore contemplates the provision of a device of this character which can be precision-made; which will draw oval or elliptical figures in various sizes within its range, with speed and precision and which will constitute a dependable and accurate drafting instrument.

Referring to the accompanying drawings, in which an illustrative embodiment of the invention is shown, Fig. 1 is a plan view of the improved drawing instrument, constructed in accordance with the invention; Fig. 2 is a horizontal sectional view on the line 2—2 of Fig. 4, looking in the direction of the arrows; Fig. 3 is a diagram illustrating the principle of operation of the device; Fig. 4 is a vertical sectional view through the device; Fig. 5 is a vertical sectional view taken at right angles to that of Fig. 4; Fig. 6 is an elevational view of one end of the instrument, and Fig. 7 is a view of the opposite end.

The device includes a housing 1, shown as being relatively flat so that it may be placed firmly upon a surface upon which the figure is to be drawn, and substantially square in shape. The housing may, of course, be of other shape if desired. In the form shown, it is provided with the four vertically-disposed side walls 2, 3, 4 and 5. The top plate 6 of the housing is provided with a circular aperture 7 to disclose a rotatable disk 8 mounted below it, said disk being rotatively supported upon an annular shelf member or ledge 9 located within the housing and provided with the central aperture 10 through which the under face of the disk 8 is exposed. An annular spacer 11 is located adjacent the peripheral edge of the disk 8 to accurately center the disk in the housing, permitting its manual rotation as herein described, but maintaining it from lateral displacement.

The entire peripheral edge of the disk 8 is toothed as indicated at 12, and the side wall 5 of the housing is slotted, as indicated at 13 (Fig. 6) to permit of the protrusion of a portion of the toothed edge 12 of the disk 8, as clearly seen in Figs. 1, 2 and 6. Rotatively mounted on a spindle 14 on the outside of the wall 5 of the

2

housing is a pinion 15 in meshed engagement with the toothed edge 12 of the disk. A second pinion 16, rotative on a spindle 17, meshes with the pinion 15 and also meshes with the toothed edge 18 of a disk 19 located within the housing 1 and below the disk 8, the disk 19 being similar in size and construction to the said upper disk 8.

Through the arrangement above described, it will be noted that there is rotatively mounted within the housing 1, a pair of spaced, similar, toothed-edge disks 8 and 19, and that these disks are caused to rotate together, at the same speed and in the same direction when one of them, or that shown at 8, is manually rotated, by means of the intermesh of the disks with the co-operating pinions 15 and 16. The lower disk 19 is rotatively supported upon the inturned flange 20 of an annulus 21 secured in the lower portion of the housing 1, and a portion of the toothed edge 18 of the lower disk 19 protrudes out of the side wall 5 of the housing to reach and mesh with pinion 16, as clearly seen in Fig. 6. If desired, the portions of the disks 8 and 19 which project from the housing, as well as the pinions 15 and 16 can be covered and thus protected by a suitable cover member, not shown for simplicity in illustration.

The lower disk 19 is confined between the upper face of the flange 20 and the bottom of a ring 22 secured to the walls of the casing, said ring 22 forming a ledge or shelf for a slidable, slotted bar 23 provided for most of its length with a longitudinally-extending slot 24. Formed in the lower disk 19 is a radially-extending slot 25 in which a setting-pin 26 is adjustable. Said pin 26 is provided with the finger piece 27 from which a threaded shank 28 extends, said shank adjustably engaging a nut 29, so that when the setting-pin is loosened in the nut 29, the pin and the nut can be slid along in the slot 25 to a desired extent, according to a scale provided on the face of the disk, and then tightened in any position of adjustment in the slot. It will be observed that the setting-pin 26 is provided with an extremity or tip 30 entering into the slot 24 in the slidable bar 23, this tip or extremity 30 of the pin 26 riding in the slot 24 of the bar 23, as seen in Fig. 4.

Bar 23 is confined between the ring 22 and a shelf or ledge 31, and slidably mounted on top of the ledge 31 is a second slotted bar 32 extending at right angles to and across the top of the first slotted bar 23. The second bar is longitudinally slotted as at 33, and movably received in the slot 33 is the tip or extremity 34 of a setting-

pin 35 similar in construction to that shown at 26, in that it has a finger-piece 36 and threaded shank 37, the latter engaging a nut 38 for holding the pin in any set position of adjustment in a radially-extending slot 39 in the top disk 8. Rising from the top face of the disk 8 is a yoke-shaped operating member 40 having a finger-piece 41 located directly over the center of the disk 8, and which is employed to manually rotate the two disks to operate the instrument.

The beam 42 constituting the translating device which draws the oval or elliptical figures, is provided at one end with a suitable sleeve-like holder 43 in which a pencil, pen, stylus or other suitable inscribing device, may be securely held. The opposite end of the beam 42 is provided with a vertically-disposed pin 44 having one end portion entering into the slot 24 in the bar 23, and its other end entering into the slot 33 of the slideable bar 32, as clearly seen in Figs. 4 and 5. Formed in the beam 42 is a longitudinal slot 45 into which extends a protuberance 46 secured to or formed on and arising from the top of the slideable bar 23 adjacent to one of its ends, as seen in Fig. 4. The end wall 4 of the housing is formed with an elongated slot 47, seen in Fig. 7, through which the beam 42 protrudes, and in which the beam is movable when drawing an oval or elliptical figure.

Briefly, the manner in which the device operates is as follows:

The mode of operation of a device of this character is based on the theory that when a radius cuts the circumferences of two concentric circles, said circles being indicated at *a* and *b* in Fig. 3, at the points *c* and *d*, then the horizontal ordinate *e-f*, cutting the circle *b* at the point *d*, and the vertical ordinate *g-h*, cutting the circle *a* at the point *c*, meet the point *i* on the line of the ellipse. In setting the instrument to draw an ellipse of a given size, the width of the ellipse to be drawn is determined by the setting of the upper pin 35 in the slot 39 of the upper disk 8. As will be noted in Fig. 1, the upper face of the disk 8 is scaled or calibrated at 48 along the edge of the slot 39, and the pin 35 is provided with a pointer 49 for use in conjunction with the scale to enable the desired setting to be secured, and thus the width of the figure to be drawn, to be secured. The length of the elliptical figure is determined by the setting of the lower pin 26 in the slot 25 in the lower disk 19, said pin 26 also having a pointer for co-operation with a scale of calibrations on the lower disk 19 situated adjacent to the slot 25 therein.

The settings of the pins 26 and 35 thus correspond to the points *c* and *d* in the diagram of Fig. 3, and the resultant positioning of the pin 44 of the beam 42 in the two slots 33 and 24 as a result of the shift of the bars 23 and 32, corresponds to the oval-defining point *i* of the diagram. As the top disk 8 is rotated by manipulation of the finger-piece 41 of the yoke 40, it will also rotate the lower disk 19 in the same direction and at the same speed. The setting-pins 26 and 35 will slide the bars 23 and 32 to the extent determined by the positions of the setting-pins in the respective slots 39 and 25, causing the pin 44 at the inner end of the beam 42 to be moved through an elliptical path, and the marking device 44a carried at the opposite end of the beam 42 to translate the movement of the inner end of the beam on a sheet of paper or other suitable surface on which the instrument is rested. The width and length of the elliptical figure so pro-

duced, will be determined by the settings of the pins 35 and 26 as heretofore explained, and since said settings are easily and accurately secured and maintained by loosening, shifting and then tightening the pins, the results secured from the instrument, from relatively small elliptical figures to increased sizes within the range of the instrument, are precise and accurate, yet can be drawn speedily and with confidence.

10. It will be understood that various modifications may be readily made in the structure without departing from the spirit of the invention, since the proportions and arrangements of the parts illustrated have been materially exaggerated in order to clearly disclose the mode of operation of the device. Hence, while I have described one embodiment of the invention, it is obvious that the same is not to be restricted thereto, but is broad enough to cover all structures coming within the scope of the annexed claims.

What I claim is:

1. In an instrument for drawing elliptical figures, a pair of rotatable disks and means by which said disks can be simultaneously rotated in the same direction and at the same speed, each disk having a radially-extending slot, a pin adjustable along each slot, a pair of crossed bars between the disks, said bars being shiftable transversely of their length and at right angles to one another, each bar having an elongated slot, one of the pins entering the slot in one bar and the other pin entering the slot in the other bar, a beam having a projection at one end entering and movable in the slots in both bars, and a reproducing element at the end of the beam opposite to that on which the projection is situated.

2. In an instrument for drawing elliptical figures, a housing in which a pair of spaced parallel disks is rotatably mounted, means for coupling said disks to cause the same to be both rotatably moved at the same speed and in the same direction when rotative manual movement is applied to one of them, a pair of slideable bars in the housing between the parallel disks, one of said bars being slideable in a direction at right angles to the direction of sliding movement of the second bar, both bars being slideable transversely of their length, the disks each having a radial slot, a pin adjustable along each slot, each pin having an element slidably engaging one of the bars, a translating device in the form of a beam carried by one of the bars and slideable longitudinally of the same, said beam being provided with a projection adjacent to one of its ends entering into slideable engagement with both bars.

3. In an instrument for drawing elliptical figures, a pair of parallel disks rotated at the same speed and in the same direction, a pair of crossed slotted bars between the disks, said bars being mounted for sliding movement transversely of their length and relative to one another and at right angles to one another, each disk having a pin adjustable radially of the disk, the pin on one disk entering the slot in one of the bars and the pin on the other disk entering the slot in the other bar, a beam having a free end carrying an inscribing device and having its other end provided with parts in movable engagement with the slots in both bars.

4. In an instrument for drawing elliptical figures as provided for in claim 3, wherein means is provided by which the beam is slideable in relation to both bars.

5. In an instrument for drawing ellipses, a

housing of substantially square shape and open at its top and bottom, a pair of spaced, horizontally-disposed gears within said housing, a face of the upper gear being exposed in the open top of the housing, a face of the lower gear being exposed in the open bottom of the housing, a slotted bar located above the lower gear and movable transversely of its length with a side-to-side sliding movement within the confines of the housing, the lower gear having a radially-extending slot, a pin passing through the slot in the lower gear and provided with means for fixedly positioning it at any selected point therein, said pin having a terminal portion riding in the slot in the bar, a beam carried over the bar and having a projection entering the slot in the bar, said beam having a portion projecting laterally of the casing and carrying an inscribing element, a second slotted bar mounted below the upper gear and above the first bar and movable transversely of its length, the second bar having a slot disposed at right angles to that in the first bar, a radially adjustable pin in the upper gear having a terminal portion entering the slot in the second bar, the projection on the beam also entering the slot in the second bar.

6. In an instrument for drawing ellipses as provided for in claim 5, wherein the gears have toothed portions protruding outside of the housing, gearing disposed between said gears and serving to drive the gears at the same speed and in the same direction when one of the gears is manually rotated, and a centrally-positioned operating handle arising from one of the gears.

7. In an instrument for drawing elliptical figures, a housing, a pair of simultaneously rotated members therein, each of said members being radially slotted, a pair of slotted bars slidable transversely of their length and relatively to the rotatable members, one of said members being slidable in a direction substantially at right angles to the direction of slidable movement of the second bar, a setting member adjustable along the slot of one of the rotatable members, said setting member having a projection entering the slot in one of the bars, a similar setting member adjust-

able along the slot in the second rotatable member and having a projection entering the slot in the second bar, and a beam longitudinally adjustable along the slot in one of the bars, said beam having a projection at one end entering the slots in both bars, and a reproducing element at the other end of the beam.

8. In an instrument for drawing elliptical figures, a pair of superimposed disks located in parallel planes, gearing means for causing said disks to rotate together when one of them is manually rotated, a pair of horizontally-mounted slidable members extending for the full diameter of the disks, each of said members being slidable transversely of its length and in a direction at right angles to the direction of sliding movement of the other member, each disk having a projection adjustable transversely across it for selective location at any desired point in the radius of the disk, each projection being in slidable engagement with one of the members in a manner to permit the projection to move longitudinally of the member which it engages upon rotation of the disks, and a beam having an end slidably connected to both of said members in a manner to cause the movements of said members to control the movements of the beam, said beam having an inscribing device that is carried through a path of movement similar to that of the end of the beam which is in slidable engagement with said members when the two disks are rotated.
